DESIGN FOR A WOMAN'S HAT

Edith F. Scheppeler, New York, N. Y.

Application October 3, 1944, Serial No. 115,565

Term of patent 7 years

(Cl. D3—13)

To all whom it may concern:

Be it known that Edith F. Scheppeler, a citizen of the United States and resident of New York city, in the county of Bronx and State of New York, has invented a new, original, and ornamental Design for a Woman's Hat, of which the following is a specification, reference being had to the accompanying drawing, forming part thereof, in which,

Fig. 1 is a top plan view of a woman's hat showing my new design. Figs. 2 and 3 are side and bottom views, respectively, thereof.

I claim:

The ornamental design for a woman's hat, as shown.

EDITH F. SCHEPPLER.
